COMBINED CANDLE AND CONTAINER THEREFOR

Janet R. Twedt, Maple Bluff, Wis.
(33 Bellerive Acres, St. Louis, Mo. 63121)

Filed Aug. 9, 1971, Ser. No. 170,410

Term of patent 14 years

Int. Cl. D26—04

U.S. Cl. D73—1 B

Fig. 1

Fig. 2

Fig. 3

Fig. 4

FIG. 1 is an isometric view of a combined candle and container therefor embodying my new design.

FIG. 2 is an isometric view thereof as it appears with the cover removed and inverted.

FIG. 3 is a side elevation of FIG. 1.

FIG. 4 is a bottom plan view of FIG. 1.

I claim:

The ornamental design for a combined candle and container therefor, as shown and described.
